UNITED STATES PATENT OFFICE.

MANUEL ARAIZA, OF VICTORVILLE, CALIFORNIA.

GEARING FOR WIND-MOTORS.

1,292,225.

Specification of Letters Patent.

Patented Jan. 21, 1919.

Application filed July 19, 1917. Serial No. 181,629.

To all whom it may concern:

Be it known that I, MANUEL ARAIZA, a citizen of the United States, residing at Victorville, in the county of San Bernardino and State of California, have invented new and useful Improvements in Gearing for Wind-Motors, of which the following is a specification.

This invention relates to gearing for windmills.

It is the principal object of this invention to provide a windmill having vanes which may be controlled to offer variable resistance to the wind without interruption of the rotation of the windmill head, said control being such as to regulate the speed of rotation of the mill and the power developed thereby under varying weather conditions, as well as to practically discontinue the operation 20 of the mill, when desired.

Other objects will appear hereinafter.

The invention is illustrated, by way of example, in the accompanying drawings in which:

25 Figure 1 is a view in side elevation illustrating the completely assembled windmill with parts broken away to more clearly disclose the sail controlling mechanism.

Fig. 2 is a view in horizontal section as seen on the line 2—2 of Fig. 1, particularly illustrating the disposition of the sail actuating elements.

Fig. 3 is a view in transverse section as seen on the line 3—3 of Fig. 1, particularly disclosing the sectional formation of one of the sails.

Referring more particularly to the drawings, 10 indicates a supporting structure upon which the rotor 11 of a windmill is carried. 40 This structure may be of any desired design and is here shown as fitted at its upper end with a bearing plate 12 through which a vertical pump shaft 13 extends. Mounted upon this shaft and resting upon the bearing 45 is a supporting collar 14. The shaft extends upwardly from this collar to support the rotor frame upon which a plurality of sails 15 are mounted. In the present embodiment of the invention four sails are

50 used, although it will be understood that any other suitable number may be utilized without departing from the spirit of the invention. These sails are of peculiar design, each one being substantially arcuate in transverse cross section, as particularly shown in Fig. 3, and having longitudinally tapering

side walls, as particularly shown in Fig. 1. This design causes the sails to readily catch the wind and utilize its power.

In order that the effective action of the 60 sails may be adjusted, each of the sail members is provided with hinged brackets 16 and 17 at their upper and lower ends. These brackets are in longitudinal alinement and are adapted to receive a hinge bolt 18 which 65 passes through both of the brackets and also through bearing members 19. These bearings are secured to angularly disposed frame members 20 of the rotor frame and therefore cause the sails to be supported at 70 an angle to the rotating shaft, as particularly shown in Fig. 1.

The upper ends are formed with yokes which constitute a part of universal joints 21. These joints are connected with driving shafts 22 which extend horizontally and are rotatably secured upon the upper plate 23 of the rotor frame. This plate is secured to rotate with the shaft 13. Mounted upon each of the driving shafts 22 are spur pins 80 ions 24 which are in mesh with vertical racks 25. The racks are slidably positioned through openings in the top plate 23 and when they are reciprocated will act to rotate the spur gears and their shafts, this motion, in turn, 85 being imparted to the hinge rods 18 and the sails fixed thereto. The racks are fixed to upper and lower sliding bearings 26 and 27 which are positioned above and below the rotor frame, respectively. These bearings 90 are fitted with keys which register with a longitudinally extending key-way 28 formed along the shaft. An intermediate supporting bearing 29 is secured to the racks and midway the distance between the bearings 26 95 and 27. By this arrangement the racks may be vertically reciprocated by a shifting rod 30 which is formed with a yoke 31 engaging a grooved collar 32 at the lower end of bearing 27.

100 In operation, the windmill is assembled as shown in Fig. 1 and its sails set to catch the wind. This is accomplished by raising or lowering the shifting rod 30 to either swing the sails out to present their cups to the 105 wind, or incline them so that the wind will not strike so forcibly. As the shifting rod 30 is moved it will act by means of the yoke 31 to raise and lower the sliding bearings 26 and 27. The racks 25 will thus be reciprocated and will cause rotation of the gears 24 110 and the drive shafts upon which they are

mounted. These shafts will act through the universal joints 21 to swing the sails upon their hinge supports.

It will thus be seen that the sails may be 5 regulated, irrespective of the speed of travel of the rotor and that the performance of the windmill may be easily controlled.

While I have shown the preferred construction of my gearing for windmills as 10 now known to me, it will be understood that various changes in the combination, construction and arrangement of parts may be made by those skilled in the art without departing from the spirit of my invention.

15 I claim:

A gear for windmills comprising the combination with a supporting structure of a bearing plate fixed upon the supporting structure, a pump shaft rotatably mounted 20 and extending vertically through the bearing plate, a supporting collar fixed upon the

pump shaft and engaging the bearing plate, a rotor frame fixed upon the shaft above the bearing plate and having angularly disposed members for supporting the sails, 25 hinged brackets fixed to the angularly disposed members, sails connected to the hinged brackets, driving shafts connected to the sails and having universal joints, spur pinions upon the driving shafts, vertical racks 30 slidingly mounted upon the shafts and through the rotor frame in mesh with the spur pinions and splined to the pump shaft, a grooved collar connected to the racks, a yoke engaging the groove in the collar and a 35 shifting rod supporting the yoke so that by operating the shifting rod the sails may be adjusted to catch more or less wind.

In testimony whereof I have signed my name to this specification.

MANUEL ARAIZA.
